UNITED STATES PATENT OFFICE.

HENRI COLOMBELLE, OF LE RAINCY, FRANCE.

APPARATUS FOR OPERATING WINDOW FRAMES OR SASHES.

1,406,154.

Specification of Letters Patent. Patented Feb. 7, 1922.

Application filed July 2, 1920. Serial No. 393,762.

To all whom it may concern:

Be it known that I, HENRI COLOMBELLE, a citizen of France, residing at Le Raincy, Seine-et-Oise, France, have invented certain new and useful Improvements in Apparatus for Operating Window Frames or Sashes, (for which I have filed applications for patents in France October 16, 1918, and April 17, 1919; in England December 22, 10 1919; in Italy November 10, 1919; in Switzerland Nov. 10, 1919; in Germany November 17, 1919; in Canada December 22, 1919, and in Belgium May 12, 1919,) of which the following is a specification.

15 The present invention has for its object a device for opening and closing of window frames or sashes with the greatest ease, and maintaining them in position in an absolutely certain manner.

20 This apparatus is constituted broadly by an extending mechanism having several successive jointed parallelograms, constructed in such a way that the front sides of one of them extended, form the rear sides of

25 the next one, such mechanism being commonly known as lazy-tongs. One of the ends of this system is attached to the window frame to be operated, while at the other end, one of the sides of the last 30 parallelogram, pivoted at a fixed point, is prolonged so as to form an operating lever. This lever has also an arc-shaped rack held normally in engagement with a fixed catch by a flat spring to hold the window frame

35 in the desired position and this rack is automatically released when a pull is exerted upon a cord, by which the operation of the window frame from a distance is effected.

In a modification of the operating system, 40 the spring is replaced by a spring having two long arms which are generally connected by a loop, the two arms are of equal length doing away with a return pulley, and the course of the cable is simplified; greater 45 security of locking is thus obtained and a greater smoothness of working.

The following description given by way of example with reference to the accompanying drawings relates to a practical constructional form of the invention, and will enable the peculiarities and uses thereof to be readily understood.

Figure 1 is a front view of the window frame.

55 Figure 2 is a section thereof on the line X—X (Figure 1) in the closed position.

Figure 3 is a similar section, the window frame being open.

Figure 4 is a detail view showing the bolt of the rack on a larger scale. 60

Figure 5 is a modification of the operating system of the window frame.

The window frame is shown at a. It is pivoted along its upper side and is composed of a rectangular frame with a division 65 bar b which carries a lug c of the extending system.

This system is constituted by arms d pivoted at each of their ends and at their centres to other arms e, so as to form the set of 70 jointed parallelograms or lazy-tongs shown in Figure 2.

The last of the arms d is prolonged at g beyond its pivot f, and acts as an operating lever. With regard to the pivot f common to this lever and to the adjacent half arm e, it is supported by a fixed pivot which is carried in the example represented by a double supporting bar h placed behind the window frame and fixed sash i. 75

On the other hand the end of the last of the arms e serves for direct attachment to the prolongation g to which is pivoted at o a rack k which is arranged concentrically with the pivot f. This rack passes between 80 two cheeks l between which is fixed a block forming a catch m (see Figure 4) with which the rack normally engages and with which at its extremity part is connected a cord q' which passes over two return pulleys p on 90 the lever g. This cord descends and hangs below the window frame, and its upper return length q² is connected to the end of the said lever g. Finally a flat spring r is arranged above the catch m and bears on the 95 rear of the rack k to hold same normally in engagement with the catch m.

The working of this apparatus is as follows:—

Starting from the closed position shown 100 in Figure 2 the length q' of the cord is pulled in order to raise the rack which by the arrangement of recess s' ensures the locking of the window frame ordinarily. The rack rises and without releasing the 105 length q' of the cord and by pulling on the length q² the opening of the window frame to the desired degree is effected.

The arm g being drawn down by the length q² of the cord oscillates about its 110 centre f and thrusts the first arm e which itself exerts its reaction on the arm d, so

that the first parallelogram opens and the others follow also, as their sides must always remain parallel in each set. When the extension of the system effects sufficient opening, the length q^2 of the cord is no longer pulled and the length q' is released thus causing the rack to drop back by its own weight or under the action of the spring r , and engage by one of its teeth with the catch m . The window frame thus remains open in the desired position, and in order to close it, it is sufficient to perform the reverse operation by lifting the rack and allowing the window frame to drop back quietly.

However, the action of the spring will not be very strong by reason of the small thickness given to the spring, and should it be desired to employ a spring which is thick, and consequently less flexible, the action becomes irregular and diminishes in accordance with the degree of opening of the window frame, and is least when the frame is bearing with its greatest weight upon the rack, for at this moment the spring will bear upon the straight portion k^1 instead of on the concave portion k^2 , and however this spring may be constituted, it will soon become fatigued and will operate in a defective manner.

The arrangement shown in Fig. 5 will entirely overcome these drawbacks. In this figure, similar parts are indicated by the same letters, but the spring is now composed of a steel wire having two arms of considerable length r^1 and r^2 , connected by a loop s . This arrangement affords a great flexibility, whereby a spring of medium force can be used to produce at all times a sufficient pressure to prevent the disengagement of the rack from the stop in all positions of the frame, whatever may be the weight of this frame. In order to facilitate the mounting, the spring is caused to bear simply upon the operating lever by means of a small slide v , and in this manner the rack together with its spring can be readily removed, all that is required being to take apart the articulation o .

As concerns the length covered by the cable, it will be clearly observed that it has a reduced length in Fig. 5, this being obtained by giving the same length to the two arms k and g , whereby one of the pulleys p can be omitted, and in this latter case the operation is easier to perform.

However, a slight deflection has been given at the point x to the bar h supporting the operating device, this deflection permits of

reduction in space occupied at top and bottom, by bringing the upright near to the plane of the fixed sash, and it permits also of use being made thereof directly to fix the top m of the rack.

It will be seen that this system is smooth and easy in working and the heaviest window frame may be operated with little effort (by giving the arm g suitable proportions) and with the maximum of safety from a distance. By means of the rack system, should the cord be allowed to escape, or if it should happen to break, the window frame will at once be arrested automatically, rendering all breakage of the glass or panes impossible.

It must be understood that the particulars above given are in no way limitative and that while still keeping within the scope of the invention, any desired modifications of detail and desired proportions may be made in the apparatus according to circumstances.

I claim—

1. Apparatus for operating windows, comprising lazy-tongs pivoted to the window, a pivoted extensor for the lazy-tongs, one of its sides prolonged to form an operating lever, a fixed catch, a rack pivoted at the end of said extensor held normally in engagement with said catch, a spring acting on said rack, and a cord one end of which is connected to the lever controlling the movements of the lazy-tongs for causing the window frame to open, while the other end is connected to the free end of the rack, for disengaging said rack from said catch to permit actuation of the lazy tongs, said spring causing automatic engagement of the rack with the catch when the cord is released.

2. A window operating device, comprising a supporting bar, a lever pivoted thereto, a lazy-tongs connected to said lever and the window to be operated, a rack pivoted to said lever, a lug on said bar for engaging the rack, a spring between said rack and said lever, said spring having its ends straight and extended, one of said ends fastened against movement and the other slideable, a pulley on said lever, and an operating cord passing over said pulley and connected to the end of said rack and a cord connected to the end of said lever.

In witness whereof, I have hereunto signed my name in the presence of a subscribing witness.

HENRI COLOMBELLE.

Witness:

CLEMENT S. EDWARDS.
